UNITED STATES PATENT OFFICE.

JOHN A. SCOTT, OF DEDHAM, MASSACHUSETTS, ASSIGNOR TO THE SENTINEL MFG. CO., OF NEW HAVEN, CONNECTICUT, A CORPORATION.

TIMING MECHANISM.

Application filed February 20, 1924. Serial No. 693,891.

To all whom it may concern:

Be it known that I, JOHN A. SCOTT, a citizen of the United States, residing at Dedham, in the county of Norfolk and State of Massachusetts, have invented a new and useful Improvement in Timing Mechanisms; and I do hereby declare the following, when taken in connection with the accompanying drawings and the characters of reference marked thereon, to be a full, clear, and exact description of the same, and which said drawings constitute part of this application, and represent, in—

Fig. 1, a view in front elevation of one form which a timing mechanism, embodying my invention, may assume with the parts thereof in the position due to them prior to setting it.

Fig. 2 an edge view thereof.

Fig. 3 a view corresponding to Fig. 1, but with its several parts in the positions due to them when the mechanism is set for automatically shutting off the gas, after the lapse of a predetermined interval.

Fig. 4 a corresponding view with the parts as set for the turning on of the gas, after the lapse of a predetermined interval.

Fig. 5 a detached, perspective view of the operating-shaft with its gas-control cam constituting the ultimate operator of the mechanism.

Fig. 6 a corresponding view of the oscillating-sleeve, with its spring, which is broken away.

Fig. 7 a detached, perspective view of the upper end of the operating-lever or manual.

Fig. 8 a detached, perspective view of the buffer, with its buffer-detent lever.

Fig. 9 a detached, perspective view of the valve-detent lever, the buffer-kick-off, and the link uniting them.

Fig. 10 a detached, perspective view of the brake employed for stopping the time-movement.

My invention relates to an improved timing mechanism primarily designed for the fuel-control of cook-stoves, though available for use in a variety of situations where it is desired to effect an operation after the lapse of a predetermined time, the object of my present invention being to produce a compact and reliable timing mechanism of the character described, constructed with particular reference to giving the operator the option between two movements, such as,

in the case of the use of the mechanism in conjunction with a cook-stove, shutting off the gas automatically, after the lapse of a predetermined time, or automatically turning the gas on, after the lapse of a predetermined time.

With these ends in view, my invention consists in a timing mechanism having certain details of construction and combinations of parts as will be hereinafter described and pointed out in the claims.

As shown herein, my improved mechanism is installed upon and between front and rear case-plates 11 and 11^a, united by pillars 12. Between these plates I locate a smaller time-movement of standard construction, having front and rear movement-plates 13 and 14, pillars 15 uniting such plates, main-spring 16, main-wheel 17, ratchet-wheel 18, pawl 19, main-arbor 20, and a friction device mounted upon the arbor and comprising a washer 21, a helical spring 22, and an adjusting nut 23 mounted upon a threaded section 24 of the arbor. The friction mechanism just described is designed to permit the reverse movement of the winding-arbor, and corresponds in general construction and function to the friction mechanism forming the subject-matter of United States Patent No. 1,150,514, dated August 17, 1915, on the application of Joseph W. Gibney. The main-wheel 17 is connected by a train of the usual intermediate wheels and pinions, not shown, with a balance-wheel 25 on a balance-staff 26.

The projecting forward end of the main or winding-arbor 20 mounts a setting-lever 27 provided at its respective ends with finger-buttons 28 and formed at one end with a pointer 29 sweeping over the graduations of a dial 30 fastened to the front case-plate 11 by short studs 31. A stop-pin 32, located at the zero point in the graduations on the dial 30, limits the movement of the said setting-lever 27 to slightly less than one complete revolution.

The winding-arbor 20 carries a tripping-cam 33, located between the front case-plate 11 and an intermediate, auxiliary plate 34, located directly in front of the front movement-plate 13, as shown in Fig. 2. The said cam 33 coacts with an anti-friction roller 35 mounted in the lower end of a valve-detent lever 36, rocking upon a pin 37 in the aux-

iliary plate 34, and formed at its upper end with a hook 38 engaging with one or the other of two teeth 39 and 40, formed in a flange 41 at the forward end of a sleeve 42 having limited oscillating movement upon the operating-shaft 43 of the mechanism, the said teeth functioning in effect as detent-engaging abutments. Of these two teeth 39 and 40, the former is located further from the axis of the said shaft 43 than the latter, so that, when the hook 38 of the valve-detent lever 36 is disengaged from the tooth 40, it will catch the tooth 39, as will be hereinafter described. The said shaft, which is journaled in the upper portions of the plates 11 and 11^a, projects through the frame for the non-rotatable application to it of an operating-lever 44, located in front of the case-plate 11, provided at its lower end with a knob 45, and constituting the manual by which the setting of the mechanism, by the setting-lever 27, is made effective.

The projecting rear end of the operating-shaft 43 carries a gas-control cam 46, the nose 47 of which coacts with the rounded head 48 of a valve-stem 49 of a gas-control valve 50 (not shown in detail) in a gas-supply pipe 51. The said cam 46 constitutes, as it were, the ultimate operator of the mechanism in the broad view of my invention, and will be so referred to in the claims appended hereto.

The operating-sleeve 42 carries a spiral spring 52, the opposite end of which is fastened to the upper left-hand pillar 12 and which exerts a constant effort to turn the sleeve counter-clockwise.

The said sleeve 42 is coupled with the shaft 43 by means of a square pin 53, normally held in engagement with a shoulder 54 at the right-hand end of a transverse cut at the rear end of the sleeve by the spring 52, so that, when the manual or operating-lever 44 is swung clockwise, the sleeve 42 is turned by and with the shaft 43, whereby the said spring is energized and one or the other of the teeth 39 and 40, at the forward end of the sleeve, brought into position to be engaged by the hook 38 of the valve-detent lever 36.

When the hook 38 of the lever 36 is disengaged from one or the other of the teeth 39 and 40 by the action of the tripping-cam, the sleeve 42, shaft 43 and lever 44 are released to the power of the spring 52, which oscillates the sleeve and shaft and snaps the lever, as it were, from left to right or counter-clockwise. Now, to check the lever when so snapped, either in its intermediate or lowermost position, as the case may be, and neutralize the shock upon the immediately-related parts of the mechanism, I employ a buffer 55, consisting of a piece of rubber or equivalent material, located in a buffer-case

56 hung by its upper end upon a stud 57 in the front case-plate 11. For swinging the said buffer into its upper position, in which it checks the operating-lever 44 as it snaps from its upper or "gas-off" position into its middle or "gas-on" position, I employ a buffer-detent 58, pivotally connected with the lower end of the buffer-case 56 and having its upper end formed with a hook 59, adapting it to be hooked over the forward end of the upper left-hand pillar 12, which is suitably flattened at 12^a for the purpose. The hook 59 is engaged with the pillar 12 as aforesaid, against the tension of a long flat spring 60, which tends to maintain them in engagement. For lifting the detent 58 into position for engaging its hook 59 with the part 12^a of the pillar 12, the detent is furnished with an inwardly-projecting cocking-pin 61, the underface of which is engaged by a lifting-pin 62 in the flange 41 of the operating-sleeve 42.

For unhooking the detent 58 from the pillar 12, so as to permit the buffer to retire into its lowermost position under the pressure of the flat spring 60, I employ a buffer-kick-off lever 63, turning on a pivot 64 in the front case-plate 11 and having its lower end pivotally connected with one end of a link 65, the opposite end of which is connected with the valve-detent lever 36 near the lower end thereof.

For stopping the time-movement, after it has discharged either one of its releasing functions, I employ a flexible shoe 66, positioned to be engaged with the periphery of the balance-wheel 25, and mounted in an arm 67 (Fig. 10), mounted upon the inner end of a rock-shaft 68, journaled in the movement-plates 13 and 14 of the said time-movement, and provided at its forward end with an angular lever 69 having an upstanding-arm 70 and also mounting an upstanding spring 71. A helical spring 72, attached at one end to the arm 67 and at its opposite end to the movement-plate 14, tends to hold the shoe 66 out of engagement with the balance-wheel 25.

A spring 73, provided for maintaining the hook 38 of the lever 36 in engagement with one or the other of the teeth 39 and 40 of the sleeve 42, also tends to force the anti-friction roller 35 in the valve-detent lever 36 into engagement with the tripping-cam 33.

As already explained, my improved timing mechanism is constructed with particular reference to giving the user of it the choice between two actions,—namely, either that of automatically turning off the gas, after the lapse of a predetermined time, or turning on the gas, after the lapse of a predetermined time. The operation of the apparatus, to effect either one of these two purposes, will be described separately, as

used by a housewife for the control of a cook-stove.

In case the housewife desires to have the gas turned off, after the lapse of a predetermined time, she turns the setting-lever 27, to bring its pointer 29 over the graduation on the dial 30, representing the time which she wishes to have elapse before the automatic turning off of the gas. In setting the lever 27 as described, she has turned the main winding-arbor 20 and so wound the spring 16 and also turned the point of the tripping-cam 33 away from the roller 35 carried by the valve-detent lever 36. She now swings the operating-lever or manual 44 by its handle 45 from its normal or lowermost position in which it is shown in Fig. 1, to its intermediate or "gas-on" position, in which it is shown in Fig. 3, whereby the shaft 43 is turned clockwise and hence the ultimate operator or gas-control cam 46, the nose 47 of which operates the valve-stem 49 to turn on the gas. At the same time, the square pin 53 in the shaft 43, acting against the shoulder 54, turns the sleeve 42 with the said shaft 43, whereby the tooth 39 in the flange 41 of the sleeve, is brought into position to be engaged by the hook 38 of the valve-detent lever 36, in which position it is now held by the spring 73. This turning of the lever 43 has also energized the spring 52. Also the pin 62 has moved away from the arm 70 of the lever 69, permitting the spring 72 to draw the shoe 66 away from the periphery of the balance-wheel 25, thus allowing the time-movement to start and run. The time-movement now slowly turns the main-arbor 20 clockwise, whereby the point of the tripping-cam 33 is brought into engagement with the roller 35 with the effect of rocking the lever 36 against the tension of its spring 73 and so as to disengage its hook 38 from the tooth 39 of the flange 41 of the sleeve 42, thus releasing the said sleeve to the action of its spring 52, by which the said sleeve is now turned counter-clockwise together with the shaft 43 and the lever 44, the snappy downward movement of which is checked by the buffer 55, which is now in its lowermost position, as shown in Fig. 1. This partial, counter-clockwise rotation of the operating-shaft 33 swings the nose 47 of the cam 46 out of engagement with the head 48 of the valve-stem 49, releasing the same to the action of the valve-spring 74. The gas is thus automatically shut off. At this time also the pin 62 engages with the arm 70 of the lever 69 and swings the same against the power of the spring 72 and so applies the brake-shoe 66 to the balance-wheel 25 and stops the running of the time-movement.

On the other hand, if the housewife elects to have the gas turned on automatically after the lapse of a predetermined interval,

she turns the setting-lever 27 clockwise as before, and with the effect already described. She now grasps the knob 45 of the lever 44 as before, and swings the lever clockwise into its uppermost or "gas-off" position, as shown in Fig. 4, whereby the tooth 40 of the flange 41 of the sleeve 42 is brought into position to be engaged by the hook 38 of the valve-detent lever 36. During the latter portion of this upward movement of the lever 44, the lifting-pin 62 in the flange 41 engages with the lower face of the cocking-pin 61 in the buffer-detent lever 58, and lifts the same, whereby the buffer is swung into its upper position, as shown in Fig. 4, and also whereby the hook 59 of the buffer-detent 58 is hooked over the part 12^a of the upper left-hand pillar 12. In this longer upward sweep of the lever 44, the nose 47 of the cam 46 has momentarily opened the gas-valve 50, and then passed the same, so as to permit it to be re-closed by its spring 74. This swinging movement of the lever 44 has again started the time-movement, which, as before, slowly turns the arbor 20 and cam 33 counter-clockwise until the nose of the latter engages with the roller 35 in the valve-detent lever 36 and causes the hook 38 thereof to be disengaged against the tension of the spring 73 from the tooth 40 in the flange 41 of the sleeve 42. The spring 52 now acts to reversely turn the operating-sleeve 42, the high tooth 39 of which will be engaged with the hook 38, so as to check such turning of the sleeve, while the shaft 43 and lever 44 are checked by the buffer 55, now held in its advanced or uppermost position. This movement of the shaft 43 and cam 46 effects the turning on of the gas and the stoppage of the time-train, the latter by the engagement of the pin 62 with the spring-arm 71 of the lever 69, the pin 62 having been snapped over the arm 71 during the latter portion of the turning of the sleeve 42, in the movement of the lever 44 into its upper or "gas-off" position. Inasmuch as the time-movement was stopped as described when the gas was automatically turned on, the gas will remain turned on until the housewife turns the setting-lever 27 for the short distance required to bring it into its zero position, when the point of the cam will further rock the lever 36 with the effect, first of all, of swinging the buffer-kick-off 63 against the edge of the buffer-detent lever 58, so as to disengage its hook 59 from the upper left-hand pillar 12, after which the buffer will immediately retire to its lowermost position, under the influence of the flat spring 69. This last action is immediately followed by the disengagement of the hook 38 from the tooth 39, permitting the spiral spring 52 to snap the operating-lever or manual 44 into its lowermost position, this being accompanied by the turning

of the shaft 43 as required for shutting off the gas. After the mechanism has been set on either plan, the gas flow may be regulated by swinging the manual within the limits imposed by the transverse cut in the inner end of the sleeve 42.

The cam 46 is to be viewed as the ultimate operator of my improved timing mechanism in a broad view thereof, since it may be replaced by other operating means dependent upon what my improved mechanism is used to control, such as air, gas, water, steam, electric current, and so on. Therefore, in using the comprehensive term "ultimate operator" in the claims, I would have it understood that I intend to cover thereby, so far as the said feature is concerned, means of any character suited to any particular installation and do not limit myself to the cam 46 shown.

I claim:

1. In a timing mechanism, the combination with a time-movement, of setting means therefor, an ultimate operator, a manual for moving the same in one direction, yielding means for reversely moving the same, and connections between the said elements constructed and arranged to permit the operator to be manually set in an advanced position or in an intermediate position, with respect to its normal position, and to be automatically moved after a predetermined length of time from its advanced position to its intermediate position, or from its intermediate to its normal position, whereby the said mechanism may be utilized for automatically effecting either of two movements predetermined by the operator at the time of setting the device.

2. In a timing mechanism, the combination with a time-movement, of setting means therefor, an ultimate operator, a manual for moving the same in one direction, yielding means for reversely moving the same, a detent for restraining the said yielding means for holding the said operator in an advanced position, or in an intermediate position with respect to its normal position, a tripping mechanism driven by the said time-movement for operating the said detent to release the said yielding means from its advanced position to its intermediate position, or from its intermediate position to its normal position, whereby the said mechanism may be utilized for automatically effecting either of two movements predetermined by the operator at the time of setting the device.

3. In a timing mechanism, the combination with a time-movement, of setting means therefor, an ultimate operator, a manual connected therewith for moving it in one direction, yielding means connected with the operator for effecting the reverse movement thereof, a detent for holding the said yielding means in either of two positions, a tripping

mechanism driven by the said time-movement for operating the said detent to release the said yielding means from either of its two positions, and a buffer adapted to be set in either of two positions for checking the return movement of the manual.

4. In a timing mechanism, the combination with a time-movement, of setting means therefor, an ultimate operator, a manual connected therewith for moving it in one direction, yielding means connected with the operator for effecting the reverse movement thereof, a detent for holding the said yielding means in either of two positions, a tripping mechanism driven by the said time-movement for operating the said detent to release the said yielding means from either of its two positions, and a movable buffer adapted to be set in either one of two positions for checking the movement of the manual when moved by the said yielding means, the said buffer being connected with the manual for being set thereby, and with the time-movement for being released thereby.

5. In a timing mechanism, the combination with a time-movement, of setting means therefor, an ultimate operator, a manual connected therewith for moving it in one direction, yielding means connected with the operator for effecting the reverse movement thereof, a detent for holding the said yielding means in either of two positions, a tripping mechanism driven by the said time-movement for operating the said detent to release the said yielding means from either of its two positions, a buffer adapted to be set in either of two positions to check the movement of the manual when moved by the said yielding means, and connection between the said detent and operator to permit the operator to be adjusted without affecting the holding action of the detent.

6. In a timing mechanism, the combination with a time-movement, of setting means therefor, an ultimate operator, a manual connected therewith for moving it in one direction, and having normal, intermediate and advanced positions, yielding means connected with the said operator for effecting the reverse movement thereof, a detent for holding the manual in its intermediate and advanced positions, a tripping mechanism driven by the said time-movement for operating the said detent to release the said yielding means from either of its two positions, and permit it to return the manual from its intermediate to its normal position and from its advanced position to its intermediate position, a movable buffer connected with the manual for being automatically advanced thereby when the manual is swung from its intermediate to its advanced position, a detent for holding the buffer in its advanced position, and means connected

with the time-movement for releasing the buffer-detent.

7. In a timing mechanism, the combination with a time-movement, of setting means therefor, an ultimate operator, a manual for moving the same in one direction, yielding means for reversely moving the operator, connections between the said elements constructed and arranged to permit the operator to be manually set in an advanced position or in an intermediate position with respect to its normal position, and to be automatically moved after a predetermined lapse of time from its advanced position to its intermediate position, or from its intermediate position to its normal position, and means for stopping the said time-movement automatically when the operator is moved by the said yielding means from its advanced position to its intermediate position.

8. In a timing mechanism, the combination with a time-movement, of setting means therefor, an ultimate operator, a manual for turning the same in one direction and having normal, intermediate and advanced positions, yielding means connected with the said operator for effecting the reverse movement thereof, connections between the said elements constructed and arranged to permit the operator to be set in either of two positions and to be automatically moved therfrom after a predetermined lapse of time, and means for automatically stopping the time-movement when the operator moves from its advanced to its intermediate position.

9. In a timing mechanism, the combination with a time-movement, of setting means therefor, an ultimate operator, a shaft by which the same is carried, a manual for turning the said shaft, a sleeve mounted upon the shaft, having limited rotation with respect thereto, and provided with two differentiated detent-engaging abutments, a spring connected with the sleeve for turning the same in the opposite direction from which it is turned by the manual, a detent

for holding the said sleeve in either one of two positions against the power of the said spring, and means operated by the time-movement for disengaging the detent from the said abutments in the said sleeve.

10. In a timing mechanism, the combination with a time-movement, of setting means therefor, an ultimate operator, a shaft therefor, a manual connected with said shaft for turning the same, a sleeve mounted upon the shaft and having limited rotation with respect thereto, a spring for turning the sleeve in the opposite direction from that in which it is turned by the manual, a detent, means carried by the sleeve for the engagement thereof in two positions by the detent, connection between the said detent and the time-movement for the disengagement of the detent thereby, a buffer for checking the movement of the manual under the influence of the said spring, a buffer-detent for holding the buffer in its advanced position, and means operated by the time-movement for tripping the buffer-detent to permit it to retire from its advanced position.

11. In a timing mechanism, the combination with a time-movement, of setting means therefor, an ultimate operator, a manual connected therewith for moving it in one direction, yielding means connected with the operator for effecting the reverse movement thereof, a detent for holding the said yielding means in either of two positions, a tripping mechanism driven by the said time-movement for operating the said detent to release the said yielding means from either of its two positions, a buffer adapted to be set in either of two positions to check the movement of the manual when moved by the said yielding means, and connections between the said time-movement, setting means, operator and detent, whereby the releasing action of the time-movement may be manually performed.

In testimony whereof, I have signed this specification.

JOHN A. SCOTT.
